ATTORNEY

UNITED STATES PATENT OFFICE.

ELVIN O. MURDOCK, OF NEW YORK, N. Y.

DECANTING-PUMP.

SPECIFICATION forming part of Letters Patent No. 296,435, dated April 8, 1884.

Application filed August 17, 1883. (No model.)

To all whom it may concern:

Be it known that I, ELVIN O. MURDOCK, of the city, county, and State of New York, have invented certain new and useful Improvements in Decanting-Pumps, of which the following is a description in such full, clear, concise, and exact terms as to enable any one skilled in the art to which my invention appertains, or with which it is most nearly connected, to make and use the same, reference being had to the accompanying drawings, making part of this specification, and to the letters and figures of reference marked thereon—

15 Figure 1 of said drawings being a vertical section taken longitudinally through the center of said pump, and also through the center of a bottle, in which said pump is placed; Fig. 2, a side elevation of said pump and bottle, also partly in section; and Fig. 3, an end view 20 of the pump-connection with the mouth of the bottle or other vessel in which it may be used.

This pump is of the pneumatic variety, operated by forcing an atmospheric pressure upon 25 the liquid to be decanted; and it is more especially intended to pump, draw, or decant liquids out of bottles, kegs, barrels, jars, or other vessels, in which an air-pressure can be created and maintained upon the surface of 30 the liquid.

The construction and operation of the pump is described as follows, the points of novelty being designated by the claims concluding this specification.

35 In the drawings, J represents a bottle, of which the mouth is shown by L. In this bottle is set an india-rubber bulb, B, having a valve in its side at C. Through the center of this bulb a tube, A, passes down into the liquid contained in the bottle. The upper end 40 of the india-rubber bulb fits the tube A snugly, forming an air-tight joint around it. The lower end of said bulb is in the form of a cork or bung fitting snugly in the mouth of the containing-vessel, but loosely on the tube, or having 45 grooves I cut in the stopper H, Fig. 3, through which the air is forced from the bulb down upon the surface of the fluid in the bottle. These grooves may be provided at their 50 lower extremities with the valve M, opening downward, so that while admitting the flow

of air from the bulb B into the bottle or other vessel it will prevent the passage of air from the bottle back into the bulb B, when the pressure of the hand is withdrawn from the same. 55 By thus confining the air pumped into the bottle the liquid will be made to flow in a continuous stream from the mouth of the pump. This valve M is not, however, an element necessary to the successful operation of my invention, and if employed may be made of any desirable and well-known form.

60 Fig. 3 illustrates two plans on which the stopper may be constructed. In the plan X the grooves are cut directly around the tube. 65 In the plan Y the grooves or channels are cut between the internal and external diameters of the tube, having an intervening rim of rubber on each side of the channels. Either plan may be adopted in constructing the stopper 70 end of the bulb.

On the tube A a bulb, D, is made, into which a valve, E, is placed. This valve is made with a pendant, G, projecting upward in the tube to guide its action; and it is also made with 75 a cross-bar, F, on said pendant to regulate the lift of the valve and keep it from stopping the tube in the upper end of the valve-bulb. The valve may also be made with a small pendant, Z, on its lower side, to insure its sitting always 80 in exactly the same place; or the pendant may be omitted from both the upper and lower sides of the valve, and still make a very good pump; but if it is desired to make the pump thoroughly tight it is better to make the valve 85 with the pendants and grind it to a tight joint in the lower side or end of the valve-bulb. The valve and its bulb or chamber may be placed in the lower end of the tube, as in Fig. 1, or in the upper end, as in Fig. 2, it operating 90 equally well in either position.

The valve C in the india-rubber bulb may be of any known and convenient construction; or it may be omitted entirely, making simply a hole in the side of the bulb to be closed by 95 the hand in operating the pump.

The tube A may be made of glass or metal or other material, and the bulb B of any suitable substitute for rubber.

The operation of the apparatus is as follows: 100 The bulb B being squeezed by the hand, the air is forced down upon and confined on the

surface of the liquid contained in the bottle, by which the liquid is driven up through the tube around the valve and delivered into any suitable receiver.

5 The points of novelty in the apparatus consist of the valve C in the bulb B, the valve E in the tube D, and the valve M at the mouths of the tubes I I. These features being omitted, the apparatus is old; but without them it 10 will lack many of the advantageous features which are secured by their use. Without these valves the stream issuing from the pump will be intermittent, and the liquid in the bottle or containing-vessel will be kept in continual agitation by the return of the atmosphere through the tube A between successive 15 impulses of the hand upon the bulb; but by the addition of the valves C, M, and E the pump is not only made to throw a continuous 20 stream, but it leaves the liquid in the containing-vessel in a continual state of quiescence. This novel feature in my improved pump enables me to decant liquids from bottles containing sediment without disturbing 25 the sediment, and also, where the bottle contains liquids of different degrees of specific gravity, to pump out either liquid without disturbing the other, or causing the liquids to be agitated and mingled together.

30 My improved pump may also be employed to decant liquids from deep barrels, carboys, or vessels where one action of the bulb B does not inject a sufficient quantity of air into the vessel to force the liquid out of the mouth of 35 the pump. It is obvious that if the valves E and M were omitted in this case the liquid forced into the tube A would return to the vessel as soon as the pressure on the bulb B was released, successive actions of the said bulb 40 only causing the liquid to ascend and descend

in the tube A without being forced from its mouth; but by employing either of the valves E or M this difficulty is entirely avoided by preventing the return of the liquid down the tube A between the successive strokes of the 45 bulb B.

When the valve M is employed, the bulb D and valve E may be omitted from the tube A.

All evaporation of the liquid may be prevented by inserting a cork in the hole C of the 50 bulb B, or by making the valve M, when at rest, close the orifices I I. This is a matter of great importance in dealing with volatile liquids.

Having thus described my invention, I 55 claim—

1. The combination of a containing-vessel, J, a compressible bulb, B, provided with valve C, a tube, A, having a valve, E, and a stopper, H, provided with channels I, said tube passing 60 entirely through the bulb B, and being free to slide vertically through it, substantially as described, for the purpose specified.

2. The combination of a containing-vessel, J, a compressible bulb, B, provided with valve 65 C, a tube, A, and a stopper, H, provided with channels I and valves M, said tube passing entirely through the bulb B, and being free to slide vertically through it, substantially as described, for the purpose specified. 7

3. The combination of a containing-vessel, J, a compressible bulb, B, and a tube, A, the tube having a valve, E, and the bulb a valve or hole, C, and a stopper with channels I and valve M, substantially as described.

ELVIN O. MURDOCK.
